CLAIM

I claim the ornamental design for a bottle for cosmetics, as shown and described.

DESCRIPTION

FIG. 1 is a top PERSPECTIVE view of a bottle for cosmetics, showing my new design;

FIG. 2 is a FRONT view thereof;

FIG. 3 is a REAR view thereof;

FIG. 4 is a RIGHT side view thereof;

FIG. 5 is a LEFT side view thereof;

FIG. 6 is a TOP plan view thereof, shown in enlarged scale; and,

FIG. 7 is a BOTTOM plan view thereof, shown in enlarged scale.

The broken lines in the figures illustrate the portions of the bottle for cosmetics and do not form a part of the claimed design.
